GAS BURNER

Harold D. Schrader, Tulsa, Okla.

Application January 15, 1932, Serial No. 586,765

3 Claims. (Cl. 158—110)

My invention relates to new and useful improvements in gas burners for use primarily for kilns in which clay products are burned but also adapted to other use, and has for its object; to provide a burner, the gas nozzle of which is calculated to eject the gas in manner whereby the gas and air will form a more perfect combustible mixture for the desired use, than has heretofore been possible; to provide an arrangement of air conduits and registers or inlets into the mixing chamber in manner whereby the mixture of gas and air will be more nearly perfect for the use stated, than has heretofore been possible; to provide a mixing block assembly for the burner and mixing chamber in form more efficient than has heretofore been known, for the use stated; to provide said burner in form and arrangement simple, cheap and easily operated and adjusted; to provide said burner in form readily removable from one kiln to another; to provide said burner in form whereby it may be readily withdrawn from the mixing chamber so that a refractory shield may be interposed between it and the combustion chamber of the kiln when the same is sufficiently hot and the burner not in use; to provide a burner adapted to properly function with equal efficiency both for low temperatures and for high temperatures and one that may be easily regulated for the various temperature changes; and to provide a gas burner whereby an incomplete combustion may be obtained when desired for treating and coloring the wares being burned.

With the above and other objects in view which will appear as the description proceeds, my invention consists in the novel features hereinafter set forth in detail, illustrated in the accompanying drawings, and more particularly pointed out in the appended claims.

Referring to the drawings, in which numerals of like character designate similar parts throughout the several views:

Fig. 1 is a view in longitudinal cross section of the complete apparatus including the gas nozzle, mixing block assembly and air register assembly.

Fig. 2 is a view in elevation of the air register assembly attached to the mixing block assembly but withdrawn from the face thereof with a heat resisting shield interposed between it and the furnace or kiln.

Fig. 3 is a partial front view in elevation of the air register assembly.

Fig. 4 is a view of an axial section of a burner head having a plurality of discharge orifices one of which is adapted to be opened and closed and

otherwise regulated while the burner is in operation.

Fig. 5 is a view in front elevation on line 5—5 of Fig. 6 showing a spider arrangement for holding the gas burner in the primary air chamber. 5

Fig. 6 is a longitudinal cross section view on line 6—6 of Fig. 5 showing a modified form of gas burner construction wherein the burner is not adjustable while in operation but is otherwise adjustable. 10

Fig. 7 is a view of gas control arrangement and showing a construction whereby the gas may be independently delivered to each of the discharge orifices in the gas burner shown in Fig. 6.

Fig. 8 is a cross section view on line 8—8 of 15 Fig. 6.

Figs. 9A and 9B are views of the burner tip of the smaller discharge orifice shown in Fig. 6.

Fig. 10 is a view in front elevation on line 10—10 of Fig. 11 showing a spider arrangement for holding the gas burner in the primary air chamber. 20

Fig. 11 is a longitudinal cross section view of another modified form of construction of a gas burner and also of a primary air chamber wherein a surface of refractory material is used to impinge the gas directed toward said refractory surface from one of the discharge orifices of the burner. 25

Fig. 12 is a partial cross sectional view of the said burner construction. 30

Fig. 13 is a view in elevation on line 13—13 of Fig. 11 showing a construction providing ducts to the discharge orifices of the burner.

Figs. 14A and 14B are views in elevation of one of the burner tips of the burner shown in Fig. 11. 35

Figs. 15C and 15D are views of a preferred form of construction of a single burner mixing block assembly with C, showing a front elevation of the same and D showing a longitudinal cross section thereof.

Fig. 16 is a view in front elevation of a preferred form of construction of a nest of mixing block assembly for a plurality of gas burners.

Fig. 17 is a longitudinal cross sectional view of a gas burner provided with means of supplying a forced draft in the primary air passage way and also of a modified form of construction of the gas delivery ducts to the burner. 45

Fig. 18 is a cross sectional view of the same on line 18—18 of Fig. 17.

Fig. 19 is a cross sectional view of the same on line 19—19 of Fig. 17.

Figs. 20A and 20B are views in elevation of the burner tip shown in Fig. 17. 55

Fig. 21 is a view of the mixing block assembly on line 21—21 of Fig. 1.

In Figs. 1 to 4 inclusive, 1 represents the wall of the kiln or furnace, 2 generally the mixing block assembly therein with 2a a frame therefor which supports the hereinafter mentioned air register assembly. 3 is the secondary air duct formed between the member 3b of the mixing block assembly 2 and the hereinafter mentioned collar 5b. 4 is an auxiliary air duct formed in member 4b of the mixing block assembly 2. 5 is the primary air duct which for convenience as well as efficiency is formed by a short collar 5b held in the air register assembly instead of in the mixing block assembly.

The position of the exits of air ducts 3, 4, and 5, are indicated by numerals 3a, 4a, and 5a, respectively and the mixing of gas and air occurs from the burner tip where the gas enters thruout the mixing block assembly and into the combustion chamber proper. 6 represents generally the air register assembly which is slidably mounted on the mixing block assembly by means of bars 7 attached thereto, through projecting arms 8 extending from said register. This slidable mounting permits the entire burner and air register assembly to be withdrawn from the face of the mixing block assembly and to interpose a shield 9 of a refractory substance between the register with its burner mounted therein and the furnace or kiln when the burner is not in use and heat is to be retained in the kiln. It also permits the air register assembly to be bodily removed from the mixing block assembly of one particular kiln and used elsewhere.

The air register assembly 6 carries in it openings or ducts which are a part of the tuyères in the apparatus, with 10 representing the duct into the primary air passageway 5, and 11 representing the duct into the secondary air passageway 3, and 12 representing the duct into the auxiliary air passageway 4. Dampers are provided for the various passageways, 13 being the damper for the primary duct 5, and 14 being the damper for the secondary air duct 3, and 15 being the damper for the auxiliary air duct 4. It will be noted that the dampers 14 and 15 are slidably mounted on the bars 16 and may be moved to and away from the face of the air ducts in the register, and that the damper 15 is mounted directly on the damper 14 by means of its respective bars held on the damper 14, and that it may be locked thereon by thumbscrews 17. All of the dampers are likewise capable of being locked on their respective bars by means of similar thumb screws shown. The damper 13 is, however, slidably mounted on the outer gas pipe 18.

The gas conduits and burner head are located preferably along the axis of the mixing block assembly and register and consist of a gas conduit or pipe 18 with the burner head 19 mounted thereon and an inner gas conduit or pipe 20 positioned concentric of said pipe 18 and located therein and which is also connected into said burner head 19. Both of said gas conduits are connected into the source of supply of said gas. The outer conduit is connected thereto thru an L 21 and into a valve or cutoff 22 and hence into the T 23 which is connected with the general supply conduit 24 and leads to the discharge orifice 25. The inner conduit 20 is connected into the common source of gas supply thru a stuffing box 26 mounted on the outer conduit 18 into which stuffing box said conduit 18 is

passed and with an opening or openings 27 thru said inner conduit communicating with the aperture or apertures 28 of a spacer cage 29 which in turn communicates with a port 30 in the stuffing box chamber which in turn communicates with the T 23 thru a valve or stop cock 31 and pipe nipples union and an L as shown in the drawings. The conduit 20 is plugged after having vented into the spacer cage and the packing element 32 packs off the conduit 20 from atmosphere while the packing element 33 packs off said conduit 20 from the conduit 18, as the two packing elements mentioned confine the passage of the gas from port 30 to conduit 20. Conduit 20 leads to a discharge orifice 34 in the burner head. The arrangement of valves 22 and 31 permits of an independent regulation of the flow of gas to each of the discharge orifices 25 and 34 or a total cutting off of the gas supply to either orifice. The packing gland 35 compresses the packing elements 32 and 33 to pack off in the stuffing box 26.

Concerning the gas burner itself and more particularly its discharge orifices and their regulation, in Fig. 4 the enlarged drawing of the burner head 19 shows a truncated cone 36 threaded on said pipe 20, the same also being shown in Fig. 1, which provides a bearing for the pipe 20 to retain its center alignment so that the lips of the discharge orifice 25 conform to each other. Member 36 also serves as a jam nut or thrust flange on one end of the pipe 20. The pipe 20 continues thru said member 36 and on its end is permanently affixed the burner tip 37 of orifice 25. The other end of pipe 20 is threaded as at 38, on which thread is a lock or jam nut 39 held for convenience within a cage in the end of the stuffing box gland 35. At the end of the pipe 20 is a knob or handle 40 secured thereto by means of which pipe 20 may be moved longitudinally, to open, close and otherwise regulate the discharge orifice 25, which may be done by pulling backward on said knob, thus forcing the truncated cone 36 into frictional contact with the body portion of the burner head 19, whereupon the pipe 20 may be turned in its threads in said member 36 to cause the orifice 25 to be regulated, opened or closed as may be desired, after which the jam nut 39 may be turned to lock the pipe 20 in its desired position. The ducts, 41 in the body portion of the burner head 19, at all times communicate between said orifice 25 and said conduit 18, in the same manner as in the head shown in Fig. 6, and the orifice is regulated as aforesaid solely by the movement of its burner tip 37.

The burner tip 37 also serves as a container or body portion for the discharge orifice 34 which communicates with pipe 20. This last named orifice has a burner tip 42 threaded into the burner tip 37 and recessed as at 43 to communicate with the end of pipe 20 on which the burner tip 37 is held. The burner tip 42 is provided with ducts 44 leading from said recess 43 into an annular recess at the orifice 34. This arrangement is also shown for the small orifice burner tip in Fig. 6, and the corresponding ducts are clearly shown in Fig. 9 of the burner tip mentioned. The burner tip 42 at the orifice 34 is not adjustable to vary the orifice while the burner is in operation, but it may be adjusted when not in use by screwing it in or out of the member 37. A spacer washer of desired thickness may be inserted abutting between the end of the pipe 20 and the threaded member 42, similar to the arrangement of spacer washers shown in Fig. 6.

Consider now the second set of drawings Figs. 5 to 9 inclusive, a modified form of nozzle and gas delivery conduits thereto, is shown, in which a plurality of discharge orifices is used in manner similar to the use of the nozzle shown in Fig. 1. However, neither of these orifices is adjustable while the burner is in operation, although both may be adjusted prior to use. There is no occasion for the inner gas conduit to be movable, hence the gas conduits are rigidly connected to a common source of supply of gas. Independent control valves for the gas delivery conduits are provided similar to those shown in Fig. 1 and for the same purpose. In this set of drawings 50 represents generally the burner head held in a spider with ribs 51 in an annular member 52 attached to tuyère D which is integral of the air register assembly proper. E is the damper to the primary air passageway which said damper is slidably attached to the outer gas conduit pipe 53 to the burner. F is a bar slidably affixed in the annular spider member 52 and permanently affixed to the damper G. Pipe 53 corresponds to pipe 18 and pipe 54 to pipe 20 while the T 55 corresponds to the T 23 connected all into the common line from which the gas is derived, as shown in Fig. 1. H and I represent valves or stops corresponding to those of 31 and 22 respectively of Fig. 1. 56 is an orifice corresponding to orifice 25, and 64 is an orifice like unto that at 34. Ducts 57 lead from pipe 53 to orifice 56, with 58 the burner tip for said orifice, said tip being threaded into the burner head body portion 50 with recess 60 provided to communicate between pipe 54 and a recess 61 in a burner tip 62 threaded into tip 58 and with radial ducts 63 leading from said recess 61 to an annular recess at the orifice 64. Spacer washer 65 by its thickness regulates the size of the orifice 56 and spacer washer 66 likewise regulates the size of the orifice 64.

A further modification of a burner head and tuyère arrangement is shown in the group of Figs. 10 to 13, inclusive. The burner head is shown mounted and positioned in a tuyère the same as with the head in Figs. 1 and 6, with the same spider arrangement to hold it in place. The burner head also has a nozzle with two annular discharge orifices but in this arrangement the gas passing through the outer pipe 70 is conducted to the annular discharge orifice 71, through ducts 72 in the body portion 73 of the head and an annular recess 82 at said orifice, whereas the gas passing through the inner pipe 74 is conducted to the annular series of discharge vents 53 or jets 75 which perforate a ring 76 offset in its inner perimeter to form an annular recess 77 when the ring 76 is in position on the body portion 73 of the burner head. The recess 77 communicates with the pipe 74 thru ducts 78 in the body portion of the head and into which the recess 79 found in the head and into which the pipe 74 is threaded. The ring 76 is held on the head 73 by means of a shoulder on the head and a packing follower 80 threaded thereon with a packing ring 81 compressed between numbers 76 and 80. This annular series of jets 75 can not be adjusted but an entirely different ring 76 wherein the jets are placed and having a different number of jets or jets of a different size, or both, can be substituted. The orifice 71 can be adjusted by means of the threaded connection 88 of the burner tip 83 and spacer washer 84, the thickness of which would determine the width of the orifice 71.

It will be noted, however, that the jets 75 are

directed so that gas passing through the same will impinge on the wall 85 of the tuyère 86 and that this wall 85 is made of a refractory material to facilitate combustion of a part of the gas and air in the tuyère 86. Such an arrangement is highly beneficial to further the combustion which takes place in the combustion chamber. In Fig. 11 this refractory material is shown as an insert 87 in the tuyère 86.

Turning now to the arrangement of burner 10 head, nozzle, supply pipes and tuyère in which the nozzle is placed, the arrangement of nozzle to supply pipes shown in the group of Figs. 17 to 20 inclusive, is similar to the ones heretofore discussed, except that the discharge in the burner 15 tip 90 is through jets 91, and except that the means of adjusting the orifice 92 through the longitudinal movement of the inner pipe 93 is without threads, and the pipe 93 is slidably mounted through an aperture in the body portion of the 20 burner head as at 94 and thru the packing 95 in a stuffing box 96 with packing gland 97, and when in the desired position is locked by a set screw 98 in a lock ring 99 slidably mounted on said pipe 93 which resists the pressure on the burner head, 25 which pressure causes the pipe 93 to tend to move forward. Furthermore, in Fig. 17 is shown a means for providing a forced draft through the primary air passageway 100, the same being a pipe 101 through which air may be forced, and which 30 surrounds the gas supply pipes 93 and 102 at the burner, but through which the gas pipes 93 and 102 pass outside of the conduit at a bend or L 35 therein as shown, with set screw 103. The construction of the spider with ribs 104 holding the nozzle in the tuyère 100 is also somewhat different but not sufficiently so to necessitate an explanation.

In Fig. 15 is shown a preferred form of mixing block assembly for a single burner in which 110 40 represents the secondary air passageway similar to 3 of Fig. 1, and 111 four auxiliary air passageways formed by the included angles of the outer square and the alternate sides of the octagonally shaped exterior of the conduit forming the secondary passageway 110. It will be noted that in Fig. 15D the form taken by the tuyère 110 is that of an inverted Venturi tube.

Fig. 16 shows a nest of tuyère blocks or a mixing block assembly adapted to use with a number 50 of gas burners, as is often to be preferred. In this form the openings 112 constitute the secondary air passageway, being the equivalent of 110, and 113 the auxiliary air passage ways the same being 55 the equivalent of 111.

In operation, the volume of gas passed to each of the delivery orifices of the burner may be regulated, through valves 22 and 31 of Fig. 1, or H and I of Fig. 7, independently of the other; the size of one of the delivery orifices of the burner may 60 be regulated, through manipulation of the pipe 20 of Fig. 1, or the pipe 93 of Fig. 17, independently of the other; and the volume of air and its point of delivery with reference to the burner nozzle and with reference to the combustion chamber and its 65 mixing chamber, if any, or with reference to the kiln when the burner is employed in a kiln, may be regulated through the various tuyères and with the various dampers thereto as shown in the drawings, independently of the other tuyères and 70 dampers thereto; all of which makes said gas burning apparatus extremely susceptible to a wide range of control of the combustion. This is of particular advantage in the operation of kilns in which clay wares are burned, for as is well known, 75

an extreme range of temperatures is not only necessary but also a high range in the completeness or incompleteness of the combustion of the gas and air is very much to be desired and of extreme 5 importance. The regulation of the flow of the gas from the plurality of delivery orifices and the manipulation of the dampers for the tuyères permit not only of a high degree of perfection in complete combustion but permit also of regulating 10 the burners so as to obtain the desired incomplete combustion during the clay burning process, as is well known in the art of ceramics. In as much as the various tuyères shown make delivery of the air at different points with reference to the burner 15 and mixing chamber and combustion chamber, the mixture of the air and gas is still further controlled than without such an arrangement. The lining of the primary air passageway with a refractory material and the direction of one of the 20 jets of gas from one of the orifices towards this material placed in close proximity to the orifice whereby the gas is caused to impinge thereon, also renders the burner more efficient, and less liable to blow out particularly in as much as the volume 25 of gas delivered at each orifice can be independently controlled as aforesaid. The use of the special form of mixing block assembly having a modified form of Venturi tube is also to be desired as an aid to more perfect combustion.

30 The form of the mixing block assembly as shown in Fig. 15 makes for efficiency in combustion, and the nesting of mixing block assembly in form as shown in Fig. 16 where a plurality of burners is desired, as is frequently the case, not 35 only permits of a maximum volume of air to be passed through the tuyères for any given cross sectional area thereof, but also conserves the space and facilitates the regulation of the burners.

35 The bars which are mounted on the mixing 40 block assembly and which support the burner apparatus in a slidable and removable manner, permit the burner to be removed for use at another furnace or kiln when desired, as is readily apparent from the drawings, and the burner apparatus may, when desired, be pulled away from the mixing block assembly and a refractory shield as shown at 9 of Fig. 2, interposed between the burner and the furnace heat, preserving the burner apparatus against unnecessary deterioration 45 caused by the heat and also permitting the opening to be tightly sealed if desired. The two outer sets of dampers being capable of independent regulation and also being in form adapted to be locked together as one damper, also facilitates the 50 control of the combustion.

55 Further matters of operation need not be set forth because to do so would require an elaboration of the science of ceramics, which is an extremely technical matter, and those skilled in 60 that art have a knowledge of combustion and of burner operation such as will enable them to understand the operation of the burners disclosed, without further explanation.

Having thus fully disclosed my invention, what 65 I claim and desire to secure by Letters Patent is:

1. In a gas burner wherein two concentrically positioned gas conduits, one located within the other, are employed to conduct gas to a plurality of discharge orifices in said burner and wherein

one of said discharge orifices is opened and closed and otherwise regulated by moving said inner conduit in a direction longitudinal of said outer conduit, an outer conduit as aforesaid, an aperture therein adapted to be connected with the 5 source of supply of said gas, an inner conduit as aforesaid and with said inner conduit passed thru the stuffing box hereinafter mentioned, a stuffing box as aforesaid positioned on said outer conduit and adapted to receive and pack off said inner 10 conduit from said outer conduit, a packing chamber in said stuffing box and adapted to receive and retain two packing elements disposed one on either side of a spacer cage interposed between them, packing elements as aforesaid, a spacer 15 cage as aforesaid, a port in said packing chamber positioned and adapted to be connected with the source of supply of said gas and to communicate with an aperture in said spacer cage, an aperture in said spacer cage aforesaid positioned 20 and adapted to communicate with an aperture in said inner conduit, an aperture in said inner conduit as aforesaid positioned and adapted to communicate with the aperture in said spacer cage, and means of compressing said packing 25 elements in said stuffing box.

2. In a gas burning apparatus for generating heat, the combination of an air register assembly provided with two concentric air passageways, 30 annular dampers individual to each of said passageways, means carried on said air register assembly for slidably supporting the inner damper, means carried on said inner damper for slidably supporting said outer damper, gas delivering means supported by said air register assembly at 35 the center thereof, a passageway in said air register assembly thru which air is free to flow to said gas delivering means, a mixing block assembly with passageways corresponding to those in said air register assembly, and means carried by 40 said mixing block assembly for removably supporting said air register assembly.

3. In a gas burning apparatus for generating heat, the combination of a gas nozzle, a mixing block assembly, an air and gas mixing chamber 45 therein into which said gas nozzle is directed, a secondary air duct in said mixing block assembly leading into said mixing chamber, an auxiliary air duct in said mixing block assembly, an air register assembly adapted to be positioned at the face of 50 said mixing block assembly and with said air register assembly having therein a primary air duct positioned immediately about said nozzle and directed into said mixing chamber, a damper for said primary air passageway, and with said air 55 register assembly also having therein a secondary air passageway and communicating with the secondary air duct aforesaid, a damper for said secondary air passageway, and with said air register assembly also having therein an auxiliary air passageway further removed from the axis of said nozzle than is the aforesaid secondary air passageway and communicating with the auxiliary air duct aforesaid, a damper for said auxiliary air passageway, and means for interlocking the 60 damper of the secondary air passageway with the damper of the auxiliary air passageway.

HAROLD D. SCHRADER.
